UNITED STATES PATENT OFFICE.

RICHARD DAVID METCALFE AND JAMES CROXON METCALFE, OF ROMILEY, NEAR MANCHESTER, ENGLAND.

INJECTOR.

Application filed March 2, 1927, Serial No. 172,152, and in Great Britain November 22, 1926.

This invention relates to exhaust steam injectors in which a supplementary supply of live steam is provided for increasing the delivery pressure and in which an alternative supply of live steam throttled down to about atmospheric pressure is admitted when exhaust steam is not available.

The object of our present invention is to provide simplified control arrangements for the injector so as to obviate the necessity for several steam pipes between the control fitting which may be on the front of the boiler and the injector which is arranged at a low level so as to be beneath the water supply.

Our invention comprises the incorporation in the injector itself of the automatic control valves for the exhaust steam and water supplies and for providing a live steam supply to replace the exhaust steam when a supply of the latter is not available, the arrangement being such that only a single steam supply pipe with a valve thereon is necessary to control the functioning of the injector.

Our invention further comprises the provision of automatic means for ensuring that under normal conditions steam is supplied to the supplementary live steam nozzle and water is admitted to the injector before the valve controlling the admission of exhaust steam to the injector is opened.

Referring to the accompanying sheets of explanatory drawings:—

Figure 1 is a part elevation and part sectional elevation of an exhaust injector constructed and arranged in one convenient manner in accordance with our invention.

Figure 2 is partly a plan view of the injector shown in Figure 1 and partly a sectional plan view on the line 2—2 of Figure 4.

Figure 3 is a sectional end elevation on the line 3—3 of Figure 2.

Figure 4 is a sectional elevation on the line 4—4 of Figure 2.

Figure 5 is a sectional elevation similar to Figure 3 but showing a modification.

The same reference letters in the different views indicate the same parts.

As illustrated, the injector comprises an exhaust steam inlet α , a supplementary live steam inlet b with nozzle c , and inlet d for live steam throttled down to a low pressure to work the injector when exhaust steam is not available, a water inlet e and a delivery outlet f .

The driver's control fitting which is not shown and which may be mounted in any convenient position merely consists in a valve on a live steam pipe connected to the branch g of the injector.

The steam entering at g can pass direct to the supplementary live steam space b and the nozzle c . It can also pass by way of the passage h to the underside of the piston i which in its raised position holds open the spring loaded valve j controlling the flow of water from the inlet branch e to the space k around the steam inlet nozzle m . With the parts in the positions shown in Figure 3, steam from g can also pass into the space n beneath the valve o and if the steam pressure is sufficient to overcome the load of the spring p upon said valve, opens the latter and passes to the upper side of the piston q which is depressed and acting through the lever r (Figure 1) opens the exhaust inlet valve s . The spring t holds the valve s on its seat and returns the piston to its uppermost position when the steam pressure is removed from the piston. A leak aperture u is provided to allow steam to escape from between the valve o and the piston q when the live steam is cut off by the seating of the valve w on its seat y and so allow the piston to rise under the action of the spring t .

Steam from the valve chest of the engine supplying exhaust steam to the injector enters the automatic valve fitting at v and loads the valve w so as to prevent the pressure of the live steam at g from raising the valve w from its lower seat which, as shown in Figure 3, it is seated upon. If however, there is no steam pressure in the engine valve chest and therefore no exhaust steam available, the valve w is allowed to rise and seat upon the upper seating surface y when it cuts off steam from the valve o but allows steam to pass downwards through the spaces z to the passage d before referred to. A calibrated plug 6 restricts the rate of flow of steam to d in order to reduce the steam pressure to the low amount desired.

A valve 9 is provided on the atmospheric connection 10 , the said valve serving to close said connection when there is steam pressure in the branch v and allowing air to enter such branch when there is no steam therein so as to prevent any pulsating action on the valve w such as would occur in the case of a

locomotive engine where the train is travelling but the steam supply is cut off.

The valve 7 upon the inlet branch *a* serves to close the inlet for exhaust steam automatically if the pressure within the injector should from any cause exceed the pressure at the inlet branch.

In the arrangement shown in Figure 5, we employ a choke tube or nozzle *o'* in place of the delay valve *o* of Figure 3 but retard the rate at which pressure builds up above the piston *q* so as to ensure that the valve *s* is not opened until the water valve *j* has opened and steam is being delivered through the supplementary live steam nozzle *c*.

We may provide within the injector a valve for controlling the flow of supplementary live steam to the nozzle *c*, and such valve may be controlled from a point adjacent to the driver's steam control valve.

The operation of the arrangement is as follows:—

Assuming that exhaust steam is available and the driver wishes to start the injector in the normal manner, he gradually opens his steam control valve. This allows steam to enter at *g* and to pass to the supplementary steam space *b* and nozzle *c* and to the water valve control fitting shown in Figure 4 by way of the passage *h* whereupon water is admitted to the injector. Owing to the pressure of the spring *p* on the valve *o*, the latter is not able to open at first but as the driver continues to move his control handle and open his steam valve further, the steam pressure is able to force open such valve *o* and so depress the piston *q* and open the valve *s* which can now function normally. The function of the choke tube *o'* is the same as that of the valve *o*, namely, to delay the rate at which pressure builds up above the piston *q* and so the time of opening of the valve *s*. If the supply of exhaust steam fails, the valve *x* (Figure 3) will cut off the supply of steam to the valve *o* which will then close and the valve *s* will also close. Live steam will pass via the lower seating of the valve *x* to the passage *d* and take the place of the exhaust steam. The supplementary steam and the water supply will not be interfered with.

It will be seen that the valve *o* has a delaying action preventing the valve *s* being opened until the supplementary steam and water supplies to the injector have been established.

By reason of the employment of one steam pipe only between the control fitting and the injector and an ordinary type of steam valve as such control fitting, we simplify and improve the exhaust injector installation.

We do not limit ourselves to any particular arrangement of the injector nozzles.

What we claim is:—

1. An injector comprising a live steam inlet,

an exhaust steam inlet and a water inlet, a normally closed valve in said water inlet, means to open said valve operated by said live steam, a normally closed valve in said exhaust steam inlet, means to open said valve in said exhaust steam inlet by said live steam, means to control the admission of steam to said last named operating means for said valve in the exhaust steam inlet and means to delay the passage of steam to said last named operating means after the steam is supplied to said live steam inlet.

2. An injector as claimed in claim 1 in which the steam delaying means includes a spring loaded valve.

3. An exhaust steam injector having a control arrangement comprising a single live steam pipe, an automatic control valve to which said pipe leads, exhaust and water inlets, steam operated valves controlling the admission of exhaust steam and water to the injector itself, means operated with the live steam for opening said valves, said automatic control valve controlling the admission of live steam to the opening means for the valve controlling the admission of exhaust steam and an automatic delaying means for retarding the time of opening of the exhaust steam inlet valve relatively to the time of admission of live steam and water to the injector.

4. In exhaust steam injectors, the improved control arrangement comprising a single live steam pipe with a valve thereon, an exhaust steam inlet controlling valve controlled by live steam, an automatic control valve incorporated in the injector itself, controlling the admission of live steam to operate said controlling valve in said exhaust steam inlet and a delay valve for retarding the time of opening of the exhaust steam inlet relatively to the time of admission of live steam to the injector.

5. In exhaust steam injectors, the improved control arrangement comprising a single steam pipe with a valve thereon, an exhaust steam inlet controlled by a live steam operated valve, an automatic control valve incorporated in the injector itself and delaying means for retarding the time of opening of the exhaust steam inlet valve relative to the time of admission of live steam to the injector.

6. In exhaust steam injectors, the incorporation in the injector of a fitting with a live steam supply connection thereto, a water inlet, a live steam operated valve in said inlet, means to pass a steam supply directly to the steam nozzle and to the means for operating the valve in the water supply inlet, an exhaust steam inlet and a live steam operated valve in said inlet, means for controlling the admission of steam to said live steam operated valve in said exhaust steam inlet, means for

delaying the passage of steam to said operating means for the valve in the exhaust steam inlet such that during the normal starting operation the live steam and water supplied to the injector are operated before the exhaust steam inlet is opened.

7. An injector as claimed in claim 1 in

which the delaying means is a loaded valve and there is provided a leak aperture between opposite sides of said valve.

In testimony whereof we have signed our names to this specification.

RICHARD DAVID METCALFE.

JAMES CROXON METCALFE.
